UNITED STATES PATENT OFFICE.

WESTERN UNDERWOOD, OF LOS ANGELES, CALIFORNIA.

DESIGN FOR A CAPITAL FOR LAMP-POSTS.

Application filed March 27, 1928. Serial No. 26,019. Term of patent 7 years.

To all whom it may concern:

Be it known that I, WESTERN UNDERWOOD, part thereof.
a citizen of the United States, residing at Los Angeles, in the county of Los Angeles and State of California, have invented a new, original, and ornamental Design for a Capital for Lamp-Posts, of which the following is a specification, reference being had to the accompanying drawing, forming a

The figure is a side elevation of the capital for lamp posts showing my new design.

I claim:

The ornamental design for a capital for lamp posts, as shown.

WESTERN UNDERWOOD.
